(57) **CLAIM**

The ornamental design for a liquid preparing device, as shown and described.

DESCRIPTION

FIG. 1 illustrates a perspective view of a liquid preparing device, showing my new design;

FIG. 2 illustrates a top view thereof;

FIG. 3 illustrates a bottom view thereof;

FIG. 4 illustrates a left view thereof;

FIG. 5 illustrates a right view thereof;

FIG. 6 illustrates a front view thereof;

FIG. 7 illustrates a rear view thereof;

FIG. 8 illustrates an enlarged partial view of the area indicated by dot-dash-dot-dash line VIII of FIG. 6; and, FIG. 9 illustrates an enlarged partial view of the area indicated by dot-dash-dot-dash line IX of FIG. 7.

The broken dash-dot lines indicate portions of the liquid preparing device that form no part of the claimed design. The broken dot-dash-dot-dash lines illustrate reference lines highlighting areas enlarged in the enlarged partial view. None of the broken lines form part of the claimed design.
